UNITED STATES PATENT OFFICE.

LEMUEL MAXFIELD, OF MOLINE, ILLINOIS.

LUBRICATOR.

SPECIFICATION forming part of Letters Patent No. 253,404, dated February 7, 1882.

Application filed December 8, 1881. (No model.)

To all whom it may concern:

Be it known that I, LEMUEL MAXFIELD, of Moline, in the county of Rock Island and State of Illinois, have invented certain new and useful Improvements in Lubricators; and I do hereby declare that the following is a full, clear, and exact description thereof, reference being had to the accompanying drawings, and to the letters of reference marked thereon, which form part of this specification, in which—

Figure 1 is a side elevation, and Fig. 2 a central vertical section, of my invention.

This invention relates to lubricators for steam-engines, steam-pumps, or any machinery whose motive power is steam.

The nature of my invention consists in the combination of a cylinder, a piston working steam-tight therein, and provided with a rod which passes through a stuffing-box and has a handle on its upper end, a steam-pipe leading from the boiler into the cylinder beneath said piston, an outlet-pipe leading from the oil-receptacle above the piston to the part which it is desired to lubricate, a feed or supply inlet, and drip-pipes communicating with the cylinder above and below said piston, all being constructed and arranged as will be understood from the following description.

A designates a cylinder, which is closed at both ends, and which is preferably constructed with a single removable head, A', fitted to it steam-tight.

B designates a piston, fitted into the cylinder A and suitably packed, so as to move up and down therein, steam and oil tight. This piston is provided with a rod, C, secured centrally to it, and extended through a stuffing-box, a, in the cylinder-head A'. On the upper end of the said handle is a knob, b. The chamber above the piston is designed for containing oil of any suitable kind, which is supplied to it through a cup on the upper end of a short upturned pipe, D, provided with a cut-off cock having a hand-wheel, E, on its stem. The space beneath the piston is intended to receive steam; and to supply the steam I employ a pipe, F, provided with a cut-off cock, which pipe leads to the steam-space of the boiler or to the steam-pipe.

G G designate couplings and stuffing-boxes, to which are suitably secured pipes H H'. The pipe H is made of glass, like a gage, and it communicates with the oil-receptacle above

the piston through the coupling G, and the pipe H' may lead directly into the cylinder of the steam-engine, or it may lead into the steam-pipe, if desired. This latter pipe is provided with a cut-off cock, J, for regulating the flow of the lubricating material. The steam-inlet pipe is larger in diameter than the oil-discharge pipes H H'—say about as four to one—so as to get sufficient pressure under the piston to force the oil through the said discharge-pipes H H' at all times.

K K designate two pipes, which communicate, one with the oil-space above the piston B and the other with the steam-space below this cylinder. Both of the said pipes are provided with cut-off cocks having hand-wheels d d on their stems. The pipes K K communicate with a drip-pipe, L. By these means any oil or water that may be in the cylinder A can be drawn off when refitting the parts. To move the piston down to the bottom of the cylinder A when it is necessary to refill the cylinder with oil, I close the cut-off cock in the steam-inlet pipe F and open the cock in the lower pipe, K. I then open the cut-off cock in the pipe H', when the steam will rush in above the piston and force it down.

By my invention I am able to feed any kind of oil or tallow uniformly and evenly, and I use the steam to feed the lubricant by direct pressure against the piston instead of by condensation.

I claim as my invention—
In a lubricator of the upright kind, the combination of the cylinder A, the piston therein provided with a rod extended through the cylinder-head, the steam-supply pipe provided with a cock, the glass gage and oil-outlet pipe H, communicating with the oil-chamber above the piston, the pipe H', communicating with the lower end of the pipe H, and provided with a cock and means for allowing the refuse oil and water of condensation to be drawn from said cylinder A, all substantially as described.

In testimony that I claim the foregoing as my own I affix my signature in presence of two witnesses.

LEMUEL MAXFIELD.

Witnesses:

ANDREW ANDERSON,
WILLIAM G. MORRIS.
